CUSHION COVER FOR SEAT BOXES OF RAIL-WAY LOCOMOTIVES

Arthur L. Flaharty, Winslow, Ariz.

Application November 4, 1939, Serial No. 302,929

2 Claims. (Cl. 155—182)

My invention relates to a cushion cover for use in connection with the seat-box of a railway locomotive or the like.

An important object of the invention is to provide a cover of the above mentioned character having straps for extending about the uprights of the seat-box thereby retaining the cover in place upon the seat-box.

A further object of the invention is to provide a cushion cover having straps which are adapted to be extended over one edge of the cushion cover and be connected, providing a handle at such edge, for the convenient carrying of the cushion cover.

15 A further object of the invention is to provide a cushion cover of the abovementioned character which will receive and protect a cushion, which may be inflated or formed of compressible and expandible material, such as sponge rubber or the like, and will permit of ready access to the cushion for its removal, when desired.

Other objects and advantages of the invention will be apparent during the course of the following description.

25 In the accompanying drawing forming a part of this application and in which like numerals are employed to designate like parts throughout the same,

Figure 1 is a side elevation of a seat-box of 30 a railway locomotive, showing my cushion cover applied thereto,

Figure 2 is a horizontal section taken on line 2—2 of Figure 1,

Figure 3 is a plan view of the cushion cover, 35 showing the straps separated, for the purpose of illustration,

Figure 4 is a similar view showing the straps connected for forming a handle.

Figure 5 is a front end elevation of the cushion 40 cover,

Figure 6 is a detailed transverse section through the cover, parts broken away, and,

Figure 7 is a plan view of a modified form of 45 cushion cover embodying the invention.

45 In the drawing, wherein for the purpose of illustration is shown a preferred embodiment of my invention, a cushion cover is shown comprising a top 10 and bottom 11, formed of suitably stout flexible material, such as leather, artificial 50 leather, oilcloth or the like. The top and bottom are rectangular and arranged between the top and bottom are edge sections 12, secured to the top and bottom by lines of stitching 13. A tape or binder 14 is preferably sewed over the 55 meeting edges of the top and bottom and edge

sections 12, by the lines of stitching 13. Arranged upon one side edge section 12 is an inner short flexible strap 15, formed of leather or the like. This strap extends rearwardly beyond the cushion cover. Arranged upon the forward end 5 of the short strap is an outer long flexible strap 16. The forward ends of the straps 15 and 16 overlap in contacting relation and are secured to the edge section 12 by rivets 17 or the like. The short strap 15 carries rings 17 and 18 suitably 10 secured thereto and spaced longitudinally of the same and these rings are arranged upon the outer side of the short strap. The long strap 16 is provided at its free end with a snap hook 19, facing inwardly. Arranged upon the opposite 15 side edge section 12 is an inner long flexible strap 20, formed of leather or the like. Arranged upon the strap 20 is an outer short flexible strap 21, formed of leather or the like, and the straps 20 and 21 are secured to the side edge section 12 20 by rivets 22 or the like. The short strap 21 has rings 23 suitably secured thereto and these rings are longitudinally spaced upon the short strap and are arranged upon the outer side thereof. At its free end, the long strap 20 has a snap hook 25 24, facing inwardly.

The forward edge section 12 is provided with a longitudinal slit, the edges of which are detachably connected by means of a sliding fastener 25, of any well known or preferred type. This 30 slit is arranged upon the forward edge section 12, opposite the rear edge section 12, adjacent to where the straps are secured. The cover receives a cushion 26, which may be a pneumatic inflated cushion or a compressible and expandible cushion 35 formed of sponge rubber or any other suitable material.

In the use of this form of the invention, the cover containing the cushion is placed upon the seat-box 27 in the railway locomotive cab. This 40 seat-box has a back 28, supported by uprights 29. The long strap 16 is passed about the adjacent upright and its snap hook 19 is engaged within either ring 17 or 18 of the short strap. In a similar manner the long strap 20 is passed 45 about its adjacent upright 29 and the hook 24 is engaged within either ring 23. The long strap may be passed once or a number of times about the uprights 29, as may be found advantageous. When the long and short straps are connected 50 they form closed loops encircling the uprights 29 and serve to retain the seat cover in place upon the seat-box.

The seat cover may be readily separated from the seat-box by disconnecting the long and short 55

straps. When this is done, the inner long strap 20 has its snap hook 24 engaged within either ring 17 or 18, while the outer long strap 16 has its snap hook 19 engaged within either ring 23 5 of the outer short strap 21. When the long and short straps are thus connected they lie in superposed relation in a compact manner and both long straps may be readily grasped in the hand and serve as a handle for carrying the cushion 10 cover.

In Figure 7, I have shown a slightly modified form of the invention. In this figure, the inner short strap 15 is provided with inwardly facing resilient studs 30, to enter outwardly facing 15 sockets 31 carried by the outer long strap 20. The outer short strap 21 has outwardly facing resilient studs 32 to enter inwardly facing sockets 33 formed upon the outer long strap 16. The studs 30 of the inner short strap 15 and the 20 sockets 33 of the outer long strap 16 constitute snap fasteners to connect these straps when the long strap 16 is passed about the upright 29. The studs 32 of the outer short strap 21 and the sockets 31 of the inner long strap 20 constitute 25 snap fasteners to connect these straps when the long strap 20 is passed about the upright 29. When the seat cover is removed from the seat box, the inner long strap 20 is arranged next to the edge section of the seat cover and the inner 30 short strap 15 is passed over the end of the strap 20 and the studs 30 enter the sockets 31. The outer short strap 21 is arranged next to the inner long strap 20 and the outer long strap 16 passes over straps 20 and 21 and the sockets 33 receive 35 the studs 32. The connected straps are therefore arranged in superposed relation, in a compact manner and these assembled straps may be conveniently grasped in the hand and serve as a handle for carrying the cushion cover. By providing a plurality of studs and sockets, the straps 40 may be longitudinally adjustably connected.

It is to be understood that the forms of my invention herewith shown and described are to be taken as preferred examples of the same and that 45 various changes in the shape, size, and arrangement of parts may be resorted to without departing from the spirit of my invention or the scope of the subjoined claims.

Having thus described my invention, what I 50 claim is:

1. A cushion cover for use in connection with a seat-box of a railway locomotive or the like, said cover including a top and bottom and side edges and forward and rear edges, the forward edge 55 having a slit formed therein for the passage of the cushion, a sliding fastener to close the slit, an inner short strap, an outer long strap arranged in superposed relation upon the inner short strap, said straps having their forward ends terminating adjacent to a common point, the rear ends of 60 said straps extending beyond the rear edge, means to secure the forward ends of said straps to one side edge near said rear edge, a second inner long strap, a second outer short strap arranged in superposed relation upon the second inner long strap, said second straps having their forward ends terminating adjacent to a common point, the rear ends of 65 said second straps extending beyond the rear edge, means to secure the forward ends of said second straps to the other side edge near said rear edge, the first inner short strap being provided near its free end with connecting means, the second inner long strap being provided near its free end with complementary connecting means for detachable engagement with the connecting means of the first outer long strap, the 70 connected first inner short strap and second inner long strap and the connected first outer long strap and second outer short strap forming superposed handle-sections constituting a handle for carrying the cover, the connecting means of the first outer long strap being also adapted for detachable engagement with the connecting means of the first inner short strap and the connecting means of the second outer short strap being adapted for detachable engagement with the connecting means of the second inner long strap, the arrangement being such that the straps so connected may be passed about the members of the back of a railway locomotive seat or the like for holding the cover in place.

being provided near its free end with connecting means, the second inner long strap being provided near its free end with complementary connecting means for detachable engagement with the connecting means of the first short strap, the first outer long strap being provided near its free end with connecting means, the second outer short strap being provided near its free end with complementary connecting means for detachable engagement with the connecting means of the first outer long strap, the connected first inner short strap and second inner long strap and the connected first outer long strap and second outer short strap forming superposed handle-sections constituting a handle for carrying the cover, the connecting means of the first outer long strap being also adapted for detachable engagement with the connecting means of the first inner short strap and the connecting means of the second outer short strap being adapted for detachable engagement with the connecting means of the second inner long strap, the arrangement being such that the straps so connected may be passed about the members of the back of a railway locomotive seat or the like for holding the cover 25 in place.

2. A cushion cover for use in connection with a seat-box of a railway locomotive or the like, said cover including a top and bottom and side edges and forward and rear edges, an inner short strap, 30 an outer long strap arranged in superposed relation upon the inner short strap, said straps having their forward ends terminating adjacent to a common point, the rear ends of said straps extending beyond the rear edge, means to secure the 35 forward ends of said straps to one side edge near said rear edge, a second inner long strap, a second outer short strap arranged in superposed relation upon the second inner long strap, said second straps having their forward ends terminating adjacent to a common point, the rear ends of said 40 second straps extending beyond said rear edge, means to secure the forward ends of said second straps to the other side edge near said rear edge, the first inner short strap being provided near its 45 free end with connecting means, the second inner long strap being provided near its free end with complementary connecting means for detachable engagement with the connecting means of the first short strap, the first outer long strap being provided near its free end with connecting means, the second outer short strap being provided near its free end with complementary connecting means for detachable engagement with the connecting means of the first outer long strap, the 50 connected first inner short strap and second inner long strap and the connected first outer long strap and second outer short strap forming superposed handle-sections constituting a handle for carrying the cover, the connecting means of the first outer long strap being also adapted for detachable engagement with the connecting means of the first inner short strap and the connecting means of the second outer short strap being adapted for detachable engagement with the connecting means of the second inner long strap, the arrangement being such that the straps so connected may be passed about the members of the 55 back of a railway locomotive seat or the like for holding the cover in place.

ARTHUR L. FLAHARTY.
